CLAIM

The ornamental design for a combined inner tray and retainer cap of a packaging assembly for an implantable penile prosthesis, as shown and described.

DESCRIPTION

FIG. 1 is an isometric, exploded view of a combined inner tray and retainer cap of a packaging assembly for an implantable penile prosthesis showing my new design. FIG. 2 is an isometric view of the inner tray portion, shown independent of the assembly to show aspects of the design not visible when combined.

FIG. 3 is a front side view thereof.

FIG. 4 is a back side view thereof.

FIG. 5 is a right side view thereof.

FIG. 6 is a left side view thereof.

FIG. 7 is a top side view thereof.

FIG. 8 is a bottom side view thereof.

FIG. 9 is an isometric view of the retainer cap portion, shown independent of the assembly to show aspects of the design not visible when combined.

FIG. 10 is a front side view thereof.

FIG. 11 is a back side view thereof.

FIG. 12 is a right side view thereof.

FIG. 13 is a left side view thereof.

FIG. 14 is a top side view thereof; and,

FIG. 15 is a bottom side view thereof.

The broken lines shown in FIG. 1 are shown for the purpose of illustrating exemplary environmental subject matter and form no part of the claimed design.
